UNITED STATES PATENT OFFICE.

OSIAS O. KRUH, OF SCHENECTADY, NEW YORK, ASSIGNOR TO GENERAL ELECTRIC COMPANY, A CORPORATION OF NEW YORK.

VAPOR ELECTRIC APPARATUS.

1,029,375.

Specification of Letters Patent. Patented June 11, 1912.

Application filed October 18, 1905, Serial No. 283,259. Renewed September 2, 1911. Serial No. 647,437.

To all whom it may concern:

Be it known that I, OSIAS O. KRUH, a subject of the Emperor of Austria-Hungary, residing at Schenectady, county of Schenectady, State of New York, have invented certain new and useful Improvements in Vapor Electric Apparatus, of which the following is a specification.

My present invention relates to vapor electric devices such as mercury arc rectifiers, lamps, or the like, and is more especially intended for use in connection with vapor electric devices having a plurality of electrodes, such as anodes, of the same sign. 10
15 In apparatus of this character it has been found that in practice there exists a tendency for arcs to form between anodes, or for the arc to a given anode to reverse in sign. To prevent this objectionable action taking place, I provide a novel arrangement of shields for each of the positive electrodes or anodes.

The novel features which characterize my invention I have pointed out with particularity in the appended claims. The invention itself, however, will be better understood by reference to the following description taken in connection with the accompanying drawings, which represent one 20 of the embodiments which my invention may assume in practice.

In the drawings the invention is shown as applied to a mercury arc rectifier. The Figures 1 and 2 represent modifications.

The rectifier tube consists of a highly evacuated receptacle or container of glass or other suitable material. The larger portion of the tube consists of a bulb 1 here shown as pear shaped, which constitutes the 30 condensing chamber for the mercury vapor generated in the apparatus during operation. The lower portion of the tube is provided with two oppositely extending arms 2 and 3 having a slight upward slope so that any mercury which may be condensed therein will roll down the inclined surface of the arms into the lower portion of the rectifier chamber. This lower portion is provided with two pockets, one a relatively large 40 pocket containing a body of mercury 4 constituting the cathode or negative electrode, while a small adjacently located pocket contains a body of mercury 5 operating as a starting electrode.

The positive electrodes or anodes which

coöperate with the cathode 4 may be made of some solid material such as artificial graphite or the like, and of any convenient shape, such as a hollow cylinder, plates, or the like. These anodes are indicated at 6 and 7 and are arranged within the tubular extensions 2 and 3 of the rectifier tube. When arcing takes place from the anode or anodes a spot thereon becomes for the moment the cathode center of an arc discharge. 60 The production of the cathode spot on the anode surface is doubtless due to a variety of causes. Among the more prolific causes may be mentioned the impact of mercury globules against the hot anode surface. 65 These mercury globules may be due to the dropping of condensed mercury from the walls of the rectifier receptacle, or they may consist of particles of mercury spattered from the cathode and carried along by the 70 arc discharge from the cathode and thereby projected against the anode. Moreover the arcing may in some measure be due to a radiation from the cathode of something in the nature of ultra-violet rays or the like. 75 The nature of the radiation is somewhat obscure, though the fact that such a radiation is a contributory cause of arcing is quite clear.

In order to prevent arcing I provide the 80 anodes with shields which guard them against arc provoking causes such as I have mentioned. In the case of the anode 6 the shield is indicated at 8 and consists of a cylinder of glass closed at both ends and surrounding the anode, which may be conveniently supported from a glass tube 9 which concentrically surrounds the leading-in wire 10 for the anode. Communication with the anode 6 is afforded by an opening 11 formed 85 in the underside of the shield 8 at a point not directly under the anode 6 but beyond the anode in the direction of its supporting means. The anode 7 is provided with a similar shield 12 provided likewise with a 90 communicating opening 13. During normal operation of the rectifier, the arc from the cathode 4 issues from the cathode surface practically at right angles thereto, and then passes to one or the other of the anodes 6 and 7 as the case may be. In order to reach an anode the arc turns a right angle and traverses the annular space between the anode shield and the arm of the rectifier. 95 Thus in the case of the anode 6 the arc 100 thus passes to one or the other of the anodes 6 and 7 as the case may be. In order to reach an anode the arc turns a right angle and traverses the annular space between the anode shield and the arm of the rectifier. 105 Thus in the case of the anode 6 the arc 110

passes between the shield 8 and the arm 2 of the rectifier. The arc blast is thus directed tangentially past the opening 11. The face of the opening is practically parallel to the cathode 4 so that the arc stream which has been deflected into a direction practically parallel with the cathode surface imparts a momentum to the particles in the arc stream such as to carry them by the opening 11. It thus happens that all superfluous vapor and mercury particles unnecessary to the maintenance of the current flow are projected past the opening, while only such portions of the arc stream as are required to serve as a medium for current transmission turn into the opening and pass down into the shield 8 to the anode 6. The anode is thus effectually protected from projected matter from the cathode. The closed end of the shield 20 also effectually protects the anode from the radiations from the cathode. To be effective for this purpose the material of which the shield is composed is an important matter. Glass is a good material to use for this purpose, while fused quartz, being more or less pervious to such radiations, is relatively ineffective. The opening 11 in the shield 8, being on the underside thereof, is so located as to be completely out of line with the path 30 of any condensed mercury dropping from the top of the arm 2 or rolling down the sides thereof. Moreover, it is not located directly opposite the anode 6 but is displaced longitudinally with respect thereto, 35 thus the chances for the projection of superfluous matter against the anode are still further reduced.

Of course the apparatus which I have described may be connected in circuit in a number of different ways. One system of connections is indicated diagrammatically in the drawing. In this arrangement the anodes are connected to single phase supply leads 14 and 15. The load circuit 16 carrying the rectified current is connected between the cathode 4 and the junction 17 between reactance coils 18 and 19 in shunt to the supply mains 14 and 15. The starting anode 5 is connected through a resistance 20 to one of the supply mains, as 15. The apparatus is started into operation in a well understood manner by causing momentary contact between the mercury of the electrodes 4 and 5.

In Fig. 2 I have represented a modified form of my invention. In this figure the rectifier tube 22 is the same general shape as the tube shown in Fig. 1. The arrangement of shields for the anodes is, however, different and the arrangement of the anodes themselves is also different. Thus for example, the anode 23, located in the laterally projecting arm 24 of the rectifier tube, is supported so that its free end projects, not 65 toward the inner portion of the rectifier

tube, but toward the outer end of the arm 24. The support for the anode is afforded by the leading-in conductor 25 incased in glass or other insulating material, which leading-in conductor passes through and is sealed into a small protecting portion 26 of the wall of the tube. A small bushing 27 of lava or similar suitable material surrounds the leading-in conductor at the point adjacent to the anode. This material is unaffected by the heat of the anode as would be the glass surrounding the leading-in conductor. The shield 28 for the anode 23 is tubular in form; it is closed at the end 29 which is exposed to the blast from the mercury cathode 30 and open at the opposite end 31. This shield, of course, may be supported in any suitable way as for example, by means of the tubular projection 32 concentric with the leading-in conductor 25 and sealed into the wall of the arm 24 of the rectifier tube. The arc from the cathode 30, in order to reach the anode 23 must pass into the space between the shield 28 and the tubular projection 32 of the rectifier tube, 90 and then reverse in direction in order to reach the anode 23 whereby, for reasons already set forth, the occurrence of arcing is practically eliminated. It is of course understood that the other anode 33 may likewise be provided with a shield 34 in the same way as the anode 23 is provided with the shield 28.

It is evident that various modifications in the embodiment of my invention may be made without departing from the spirit thereof for which reason I do not wish to be limited to the exact details shown and described.

I do not herein lay claim broadly to the use of shields for preventing arcing, the same being claimed in my co-pending application, Serial No. 194,520, filed February 20, 1904.

What I claim as new and desire to secure by Letters Patent of the United States, is,—

1. The combination of a receptacle or container provided with arms or projections, electrodes in each of said arms, and a shield for each electrode surrounding said electrode and closed at that side where the arm or projection opens into the main receptacle.

2. The combination of a receptacle or container having an arm or projection, an electrode located in said arm or projection, and a shield interposed in the path of particles entering said arm or projection from the main container, said shield also extending around said electrode.

3. The combination of a receptacle or container formed with a condensing chamber, a plurality of arms opening into said container, a vaporizable electrode, a plurality of solid electrodes located respectively in said arms, and shields for said electrodes,

each of said shields surrounding one of said electrodes and having an opening in the side thereof.

4. The combination of a receptacle or container provided with arms or projections, electrodes in each of said arms, and a shield for each of said electrodes, said shield extending across the free end of the corresponding electrode and along the side

10 thereof.

5. The combination of a receptacle or container provided with tubular members or arms, an electrode in each member or arm, and a shield in each member or arm between

15 the electrode and the mouth of the opening into the container of the tubular member or arm.

6. The combination of a receptacle or container, arms projecting therefrom, electrodes

located in said arms, a vaporizable electrode 20 located in said container below the openings of said arms into said container, and a shield in each arm between the electrode and the mouth of the opening of the arm into said container.

25 7. The combination of a receptacle or container, a tubular member or arm opening into the main body of the container, an electrode in said tubular member or arm, and a shield interposed between the electrode 30 and the main body of the container.

In witness whereof, I have hereunto set my hand this 17th day of October, 1905.

OSIAS O. KRUH.
